UNITED STATES PATENT OFFICE

JOSEPH ZUBATY, OF FLINT, MICHIGAN, ASSIGNOR TO A C SPARK PLUG COMPANY,
OF FLINT, MICHIGAN, A COMPANY OF MICHIGAN

CONNECTION OF DRIVING MEANS TO SPEEDOMETERS

Application filed March 9, 1928. Serial No. 260,421.

My invention relates to an improved manner of connecting driving mechanism with an indicating instrument, such as a speedometer.

This application is a continuation in part 5 of my pending application Serial No. 94,100, filed March 11, 1926 in so far as the subject matter common to the two is concerned.

When a speedometer is mounted upon the instrument board of a vehicle, it is usually 10 permissible to have the flexible driving means approach the speedometer in a vertical position. Therefore, in certain types of speedometers the shaft which is to be connected to and driven by this driving means, projects 15 down through the bottom of the speedometer casing. In some types of vehicles, however, it is considered desirable that the flexible driving means approach the instrument horizontally, in order that it will not interfere 20 with other parts of the vehicle, or be in the way of the passengers' feet.

An object of my invention, therefore, is to provide a simple fitting between the speedometer and the flexible driving means, which will 25 permit the latter to approach the speedometer in a horizontal position. This fitting may be secured to the end of the driving means, and serves as a housing for a pair of shafts which are geared together at a right angle to each 30 other, to change the direction of the drive.

Other objects and advantages will be apparent upon referring to the specification and accompanying drawings in which:

Figure 1 is a side elevation of the lower 35 part of a speedometer casing, showing the flexible drive attachment therefor.

Figure 2 is a section taken on the line 2—2 of Figure 1.

Figure 3 is a section taken on the line 3—3 of Figure 2.

Figure 4 is a view corresponding to Figure 1, but showing a modified form of attachment.

Figure 5 is a section taken on the line 5—5 of Figure 4.

The reference numeral 10 indicates the casing of a speedometer within which is held a frame 12. Journalled in the frame is a rotor shaft 14 having a squared end 16, which 50 is usually connected directly to the flexible

driving means by a coupling 18. When it is desired to have the driving means approach the speedometer in a horizontal position, the rotor shaft is connected to a shaft 20, having an enlarged end 22 which is squared to fit into the coupling 18, as shown in Figure 2. Pressed on the shaft 20 is a worm gear 24 which meshes with a second worm gear 26, pressed on a shaft 28. The shaft 28 is substantially at a right angle to the shaft 20, with its axis in a horizontal position. An enlarged end 30 is provided on the shaft 28, to receive the tip of a flexible shaft 32, which is staked or otherwise secured therein. A flexible casing 34 surrounds the flexible shaft 32.

The shafts 20—28 are supported in a fitting or housing which is composed of an upper stamping 36 and a lower stamping 38. The stamping 36 has formed on it a flange 40 around which is bent an extension 42, formed on the lower stamping 38. This serves to hold the two stampings tightly together. Held in the stamping 36 is a sleeve 44 which passes through an opening in the speedometer casing 10 and fits into a passage in the instrument frame 12. This sleeve is held in place in the frame by means of a U-shaped clamp member 46 and a screw 48 threaded into the frame 12, the clamping member bearing against a flange 50 formed on the sleeve 44. The sleeve has formed in it a groove 52 which fits a rolled-in portion 54, formed in the stamping 36. Pressed in the sleeve 44 is a bearing 56 in which the shaft 20 is journaled. The shaft 20 is held against axial movement in one direction by the enlarged portion 22, and in the other direction by the gear 24, abutting against the bearing 56. Clamped between the stampings 36 and 38 is a bearing 58, in which is journaled the shaft 28. This bearing is held against axial movement by means of a struck-in portion 60 on both stampings, which fits into a groove 62 formed in the bearing 58. It will be seen that the axial movement of the shaft 28 will be prevented in one direction by the gear 26, and in the opposite direction by the enlarged portion 30, abutting against the bearing 58. The

flexible casing 84 is inserted between the stampings 36 and 38 before they are secured together, and is staked or otherwise secured in place between them.

5 It will be apparent that the above described parts are all stampings or automatic screw-machine parts, both of which are very cheap to produce, consequently there is no expensive machine work necessary. The 10 parts are held together and in relation to each other without the use of any screw threads or bolts. Therefore, the cost of this device is much lower than it would be if the conventional construction were used.

15 In the modification shown in Figures 4 and 5, a cast housing 68 is used instead of the stampings shown in Figures 1 to 3. A shaft 70 is provided with a squared end 72 which fits into the coupling 18. On this shaft is cut 20 or mounted a worm gear 74, which meshes with another worm gear 76 cut or mounted on a shaft 78 which is at a right angle to the shaft 70. The end of the shaft 78 is squared as at 80, and fits into a correspondingly shaped 25 tip 82 on the end of the flexible shaft 84. The flexible casing 86 is secured in a sleeve 88, which is drawn up against the housing 68 by a nut 90, which is screw-threaded on the housing. In order to permit assembly of the 30 shaft 70 and gear 74 in the housing 68, a large opening is provided which is later closed by a plug 92 which is threaded into the housing 68. The lower end of the shaft 70 is journaled in the plug 92 as at 94. A 35 second plug 96 closes an opening in the housing through which the gear 76 and shaft 78 are assembled. The housing 68 is provided with an extension 98, which passes through an opening in the speedometer casing and fits 40 into a passage in the frame 12. The housing 68 is held in place against the speedometer casing by means of bolts 100, which are screw-threaded into the frame 12.

45 It will be seen that either of the above constructions may be used to provide a cheap and simple connection between the flexible driving means and the speedometer, which will permit the flexible driving means to approach the speedometer in a horizontal position. The same type of speedometer may 50 be used either in connection with a vertical or a horizontal type drive, the only change necessary being the provision of the correct kind of coupling device between the speedometer and the driving means.

55 It is thought from the foregoing taken in connection with the accompanying drawings that the construction and operation of the device will be apparent to those skilled in the 60 art, and that various changes in size, shape, and proportion and details of construction may be made without departing from the spirit and scope of the appended claims.

I claim:

65 1. In an instrument having driven means,

driving means therefor, coupling mechanism for said driving and driven means comprising an upper and a lower stamping secured together, a sleeve secured in said upper stamping, said sleeve being fastened to the instrument, a bearing held in said sleeve, a shaft connected to said driven means and journalled in said bearing, a second shaft located at an angle to the first shaft and 70 geared to it, said second shaft being connected to the driving means, and a bearing for said second shaft clamped between said upper and lower stampings.

2. In an instrument having driven means, driving means therefor, a casing for said driving means, coupling mechanism for said driving and driven means comprising an upper and a lower stamping, a flange on one of said stampings, an extension on the other stamping adapted to be bent around 80 said flange to secure said stampings together, intergeared elements, at an angle to each other, journalled within said stampings, one of said elements being connected to the driving means and the other to the driven means, the casing for said driving means being clamped between said stampings.

3. In combination with an instrument having driven means and driving means therefor, coupling mechanism for said driving and driven means comprising a pair of stampings secured together, a sleeve secured in one of said stampings, said sleeve being fastened to the instrument, a bearing held in 90 said sleeve, a shaft connected to said driven means and journalled in said bearing, a second shaft located at an angle to the first shaft and geared to the latter, said second shaft being connected to the driving means, and a bearing for said second shaft clamped between said stampings.

4. In combination with an instrument having driven means and driving means therefor, a casing for said driving means, coupling mechanism for said driving and driven means comprising a pair of stampings, a flange on one of said stampings, an extension on the other stamping adapted to be bent around 100 said flange to secure said stampings together, and intergeared elements located at an angle to each other journalled within said stampings, one of said elements being connected to the driving means and the other to the driven means, the casing for said driving means being clamped between said stampings.

In testimony whereof I affix my signature.
JOSEPH ZUBATY.
